UNITED STATES PATENT OFFICE.

CHARLES M. RHODES, OF WAYNE, PENNSYLVANIA.

GAS-ENGINE.

SPECIFICATION forming part of Letters Patent No. 540,923, dated June 11, 1895.

Application filed November 23, 1894. Serial No. 529,724. (No model.)

To all whom it may concern:

Be it known that I, CHARLES M. RHODES, of Wayne, in the county of Delaware, State of Pennsylvania, have invented certain new and useful Improvements in Gas-Engines, of which the following is a specification, due reference being had to the accompanying drawings, forming a part hereof.

My invention relates generally to that construction of engine best adapted for the use of gas, oil or the like in generating power, and has special reference to certain novel features of construction and operation in a preferred horizontal type of engine of the character stated, hereinafter set forth; to the end that the engine shall be cheap and simple in construction; in reducing to few the number of parts, reduce frictional wear of the parts to a minimum, be economic in operation and at the same time develop greatly increased power over other constructions of like character engines; the pith of my present invention residing in employing two cylinders each provided with a piston connected to one and the same crank-shaft thereby operating in unison and making in and out strokes simultaneously, and using but one driving wheel and pulley for transmitting power. Each cylinder, of course, has its independent valvular connections for the admission of the power generating element and subsequent exhausting of the same; and independent means intermittently operating the said valves, together with proper means for timely causing the explosion of the gas or other power generating element employed.

In the drawings I have shown two such views of a gas engine embodying my invention as fully illustrate, to a person skilled in the art to which my invention appertains, the construction and operation of the same.

Figure 1 is a plan view, mostly sectional, taken as to the central longitudinal axis of the engine; and Fig. 2, a side view of the engine, showing in section one of the valve-chambers to a cylinder and in dotted lines the respective ends of the valve tripping-rods in contact with the cam-wheels, together with the gearing operating the parts.

Referring now to the drawings in which the several parts are indicated by numerals, similar numerals denoting like parts wherever

found, 1 is a fly or driving-wheel (the engine is adapted for the use of two such wheels, one being shown in dotted lines in Fig. 1) and 2 the double-crank-shaft on which the same is mounted, proper bearings being provided for said shaft. Connected to said crank-shaft 2 are two piston-stems 3 each provided with a piston-head working simultaneously, that is to say, making in and out strokes together in their respective cylinders 5.

Each cylinder 5 is provided with a valve water jacket 6, divided by partitions forming two valve compartments or chambers 6^A 6^B, and having two port or valve openings in communication with the chamber of the cylinder 5, each provided, preferably, with a puppet-valve 8 8^X mounted for end to end movement only; and further provided on its under surface or bottom with an admission and exhaust port respectively 9 and 10, in open communication with the respective chambers 6^A 6^B of said jacket 6. The stems 8^A 8^B of the valves 8 8^X extend beyond the jacket 6, and on their outer ends are preferably provided with rollers or the like 8^a 8^b, all for purposes presently explained.

A high-speed-governor 11 is suitably mounted on a shaft 7 properly journaled in bearings 8^a adjacent to the crank-shaft 2 and intermediate the two cylinders 5. The respective ends of said shaft 7 are provided with a cog-gear 12 meshing with an intermediate gear 12^X and the latter in turn with a gear 13 mounted 8^b on the crank-shaft 2 (the gearing being preferably about two to one). The said shaft 7 also carries two double cam-wheels 16 16^X, and motion is imparted to said shaft 7 and its parts through the gears 13 and 12.

The cam-wheels 16 are double in construction, so to speak, that is to say: two cams in one integral construction, one of said cams 16 having an even periphery, while its component cam 16^X has an uneven or irregular shaped periphery or face that at one point thereof merges and becomes flush with the periphery of its component part 16, for a purpose yet to be explained.

Mounted horizontally in suitable bearings 100 adjacent to the valve-stems 8^A 8^B and cam-wheels 16, 16^X are two rods or shafts 19 each provided at one end with a roller 20, kept in contact with its near cam-wheel 16, 16^X re-

spectively by a spring 21 on said shafts. These rods or shafts 19 are each further provided with a cam 22 of suitable construction adapted to work in conjunction with the valve stems 8^a 8^b to open and close the valves.

The engine, of course, is provided with suitable means (not shown) whereby the gas or the like element is timely exploded upon the completion of the compression stroke of the 10 pistons.

Having now described the generic parts of an engine embodying my present invention the operation is as follows: To take in a charge of gas, the pistons being at complete "in" 15 stroke, and all the parts in the positions represented in the drawings, and the port 9 in connection with a source of gas or like supply, a turn is given the driving wheel 1, which rotates the crank-shaft 2 and its component 20 and geared parts and causes the pistons to make an "out" stroke, the roller 20 on each of the rods 19 sinking into a low depression on the periphery of its respective adjacent cam 16^x as the latter slowly rotates, and the 25 rods 19 are consequently moved toward the same by the action of their respective spring 21. This forward movement of the rods 19 causes the valve stems 8^a of the mixing chamber 6^a of the jacket 6 to ride the cam 22 on 30 the rod 19 and open the valve 8, the gas flowing through the port 9 into the chamber 6^a and thence through the open valve 8 to the piston or compression cylinder 5. Simultaneously with this action the rotating parts are 35 increasing in momentum and the roller 20 in turn travels up a presented inclined periphery of the cam-portion 6^x, pushing backward the rod 19 and permitting the gradual closing of the valve 8 as the rod-cam 22 moves away 40 from under the valve-stem 8^a, and the latter descends the cam 22, until the said valve is closed. At this time the two pistons will have completed an "out" and first stroke, the 45 charge of gas has been taken in and all port connections with the piston cylinders closed, while the governor 11 has greatly increased in speed, whereupon the pistons immediately commence their inward, second or compression stroke; at the completion of which the 50 governor has attained high speed and during the making of said stroke the roller 20 has slowly reached the highest point on the periphery of the cam-portion 16^x, which, as stated, is flush with the even periphery of the cam portion 16. At the completion of the second stroke the act of compression of the gas or like element in the chamber 5 is also completed and ignition and explosion now take place causing 55 the pistons to at once and quickly make their 60 next conjoint outer or third stroke and so imparting increased momentum to the rotating parts and driving wheel 1, and the power so obtained is transmitted thence in the usual manner, during which the governor has attained

highest speed and the roller 20 travels on the 65 even periphery 16 of the double cam 16, 16^x, thus moving backward the rod 19 and causing the valve-stem 8^b to travel the cam 22 on said rod as the latter moves under the same to open the exhaust valve 8^x. The speed of the governor now decreases as the force of the power generated as described diminishes, allowing the parts to gradually return to their first positions, the pistons now making their next "in" or fourth stroke, exhausting the exploded gas or like element through the valve 8^x, chamber 6^b and exhaust port 10; at the 70 completion of which stroke the waste gas or the like will be exhausted from the cylinder 5, the exhaust valve 8^x closed and all the parts be again in proper position to take in an explosive charge and repeat the operation of mixing, compressing, igniting or exploding and lastly exhausting charges of gas or the like for generating and transmitting power. 75

I desire it understood that I do not wish to restrict my invention to the exact construction of parts as shown and described, as it is obvious that many changes in detail of construction may be adopted without departing from the spirit of my invention strictly as such; and though I have herein shown and described my invention as employing gas as a means of generating power, slight changes of construction entirely within the scope of my invention and the ordinary skill of a person familiar in the particular art of manufacture and operation of engines of the class described would adapt the same for the use of oil or other power generating medium employed in an engine of like character. 80

I claim—

In a gas or like engine, in combination: two cylinders, a double-crank-shaft carrying two gear-wheels mounted between the same, a piston for each of said cylinders connected to said shaft and adapted to make in and out strokes simultaneously, a mixing and exhaust chamber for each of said cylinders, having valved connections therewith, and supply and exhaust ports respectively, a speed governor, two cam-wheels and two gear-wheels mounted on a shaft suitably journaled adjacent to said crank-shaft and intermediate the cylinders, motion from the gear-wheels on the crank-shaft being imparted to the gear-wheels on the other shaft, and means intermediate the cam-wheels and the valve-stems of the valves for opening and closing the valves at predetermined intervals, as and for the purposes set forth. 105

In testimony whereof I have hereunto signed my name this 1st day of November, A. D. 1894.

CHARLES M. RHODES.

In presence of—

JOHN JOLLEY, Jr.,
GEO. H. RAPSON.
